UNITED STATES PATENT OFFICE.

CHARLES H. SHEPARD, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

No. 865,806.

Specification of Letters Patent.

Patented Sept. 10, 1907.

Application filed January 24, 1901. Serial No. 44,503.

To all whom it may concern:

Be it known that I, CHARLES H. SHEPARD, a citizen of the United States, and a resident of the borough of Brooklyn, city of New York, in the county of Kings 5 and State of New York, have invented certain new and useful Type-Writing Machines, of which the following is a specification.

This invention relates to tabulating mechanisms for typewriting machines, and one of the objects of the invention is to provide a tabulating mechanism comprising a few simple parts compactly arranged upon the top plate of a typewriting machine, and having at the forward part of the top plate a convenient finger-piece for controlling both the denomination-determining mechanism and the carriage releasing devices.

Other objects will hereinafter appear.

My invention consists in certain combinations of devices, features of construction and arrangements of parts, all as will be fully hereinafter set forth and particularly pointed out in the appended claims.

In the accompanying drawings, Figure 1 is a side elevation, partly in section, of a Remington No. 6 typewriting machine, showing my improvements applied thereto. Fig. 2 is a plan of the upper portion of the machine. Fig. 3 is a front elevation of a portion of the tabulating mechanism, the parts being shown in normal position. Fig. 4 is a view similar to Fig. 3, but showing the denomination mechanism as having been adjusted to the hundreds position and the carriage feeding rack as released from its pinion. Fig. 5 is a plan of the denomination stop, the slideway therefor, and a cam whereby said stop is actuated, the parts being shown in normal position. Fig. 6 is a front elevation of the parts shown at Fig. 5. Fig. 7 is a view similar to Fig. 5, but showing the adjustment of the denomination stop which is effected by a movement of the finger piece to the position shown at Fig. 4. Fig. 8 is a side elevation of the parts shown at Fig. 7. Fig. 9 is a rear view of a bracket which is fixed upon the front portion of the top plate of the machine, for supporting certain of the moving parts. Fig. 10 is a perspective view of a rack and index forming part of the denomination stop mechanism. Fig. 11 is a perspective view of a column stop rack and its appurtenances. Fig. 12 shows details of a cam plate and gear. Fig. 13 is a cross section of a column stop rack.

In the several views, portions of the machine are omitted or broken away to more clearly disclose the invention, and similar parts are designated by similar numerals of reference.

The framework of the machine comprises a base 1, corner posts 2 and top plate 3. A platen 4 is journaled in a frame 5, which travels across said top plate, said frame having a roll 6 to run upon a shift rail 7, and

being connected in rear at 8 by a double hinge to a truck 9, which is provided with guide rolls 10 running upon a fixed rail 11. The truck is connected by a rearwardly extending arm 12 to a sleeve 13, which slides upon a third rail 14. The carriage as a whole is propelled by a spring barrel 15, which is connected by a strap 16 and arm 17 to the truck 9. The letter feed mechanism comprises a rack 18, fixed upon arms 19, which are hinged at 20 to the truck, and also a pinion 21 with which said rack is in mesh but from which it may be lifted by a swinging movement upon the hinge 20. The pinion is suitably connected to an escape-wheel 22. The type impressions are made by type 23, carried upon pivoted bars 24, which are connected by rods 25 to levers 26, having keys 27. Beneath the key levers is arranged a transverse universal bar 28, hung by rods 29 upon branches 30 of a dog rocker frame 31, which is pivoted at 32 in a bracket 33, and carries both a feeding dog 34 and a detent dog 35, and is also provided with a returning spring 36. As the parts above mentioned are in common use in said Remington machine, it is not deemed necessary to describe them more fully.

The tabulating mechanism comprises a rack 37, arranged at the front of the top plate, a pinion 38 in mesh with said rack, a rearwardly extending shaft 39 upon which said pinion is fixed, a bevel pinion 40 secured upon the rear end of said shaft, a bevel gear or segment 41 in mesh with said bevel pinion, a cam plate 42 fixed to said bevel gear, a denomination stop 43 controlled by said cam plate, and a column locating stop 44 arranged upon the truck or carriage.

The rack 37, which extends horizontally and parallel with the run of the carriage, is slidably supported upon a fixed bracket 45, by means of forwardly projecting screw studs 46 and 47, the former of which works in a slot 48, and the latter in a slot 49, said slots being formed in said bracket and extending longitudinally thereof, whereby said rack is enabled to move endwise in a right line. To effect this movement, a handle 50 is provided forwardly of and parallel with the rack, and having a finger piece or key 51 at its right-hand end. Said handle is pivoted by a hub 52 at its left-hand end (see Fig. 2) upon the rack stud 47.

The shaft 39, which carries the pinion 38 at its forward end, is horizontally journaled in front and rear bearing pieces 53 and 54, the former of which is secured upon the top plate by screws 55, which also pass down through ears 56 and 57 formed upon the bracket 45 and arranged beneath the bearing 53, whereby both the lug and the bracket are secured upon the top plate. The bracket 45 is provided however, with an additional fastening screw 58. The rear lug or bearing 54 is fastened by screws 59.

The bevel pinion 40 carried at the rear end of the shaft 39, meshes with a toothed segment 41, which is pivoted upon a vertical stud 60 (see Figs. 6 and 12), which has a shoulder 61, and whose lower end 62 is tapped into the top plate. The hub of the segment is designated as 63, and is formed with a bore large enough to receive a hub 64 provided upon the cam plate 42, the bore of the cam plate hub being adapted to fit upon the stud 60, and the two hubs being forced or otherwise secured rigidly together, so that the cam plate and segment may move as one piece. A cap screw 65 is tapped into the upper end of the stud, to prevent the plate and gear from lifting. The cam plate is horizontally arranged, and provided with an eccentric slot 66 (see Figs. 5 and 7), and also with a working edge or face 67, which is parallel with said slot. At its inner end said slot has a short straight cam portion 68.

Working in the slot 66, 68, is a vertical pin 69, which is fixed in and projects upwardly from a stop carrier 70, the latter being arranged beneath the cam plate and fitted to slide longitudinally in a box or trough 71, the said denomination stop 43 being formed integrally with said carrier and projecting upwardly therefrom in position to be engaged by the working edge 67 of the cam 42, the engaging face of said stop being beveled to fit said edge, as illustrated clearly at Fig. 7. The box 71 extends in a direction parallel with the run of the carriage and is fastened to the top plate by one or more screws 72. The box is constructed with parallel sides 73, between which is placed a long block 74, forming the bottom of the box (see Fig. 8), said sides and block being fastened together by horizontal rivets 75. The block has parallel inclined faces 76, which match correspondingly inclined faces 77, formed upon the stop carrier, so that by an endwise movement of the stop carrier, it may be lifted or cammed up from the normal position shown in dotted lines at Fig. 6, to a position where the nose of the carrier may ride upon the horizontal surface 78 of the block and the heel of the carrier may ride upon a horizontal surface 79 also formed upon said block. In the position shown at Fig. 6, the stop 43 is below the path of the column stops 44 upon the carriage; but at the initial movement of the cam plate 42, the stop carrier is forced endwise by the straight portion 68 of the cam plate slot, and during said endwise motion is forced upwardly by the inclined faces 76, 77, thereby being projected into the path of said column stops.

The extent of movement of the carrier 70 to the right after the described lifting movement thereof depends upon the extent of rotation of the cam 42, and this in turn depends upon the amount of rotation imparted to the shaft 39 by the rack 37 when the latter is slid to the right by the finger piece 51.

To facilitate the positioning of the said denomination stop, an index 80 is secured upon the stud 46 (Fig. 10) and a series of graduations is provided upon an inclined plate 81 which is formed integrally upon the bracket 45 at the right-hand end thereof. Divisions are placed upon said scale at such intervals that a movement of the index from one division to the next corresponds with the movement of the denomination stop 43 through an interval equal to a letter-feeding movement of the carriage. The said scale divisions, beginning at the left, are designated respectively as "1", "1", "10", "100", "1000", "10,000", "100,000", and "1,000,000"; and when the pointer 80 stands opposite any of said graduations, the denomination stop is in position for arresting the carriage at the proper point for beginning the writing of a number having the indicated denomination.

The hub 52 of the handle 50 is pivoted upon the stud 47 so that the handle may be depressed for the purpose of swinging downwardly an arm 82, which has a forwardly projecting pin 83 working in a longitudinal slot 75 formed in said arm, said slot having a working face or edge 85, arranged at such an inclination that a uniform downward movement of the lever may impart a uniform movement to the arm 82, irrespective of the longitudinal position of the lever. In other words, a given downward throw of the lever, when it is adjusted to the extreme right, will impart the same extent of downward movement to the arm 82 as when the lever is adjusted to the extreme left, notwithstanding that there is a change of relative positions between the pivot 47 of the lever and the pin 83. This is due to the fact that there is a lost motion which occurs between the inclined face 85 of the slot in the lever and the pin 83 when the lever is in the right-hand position, as indicated in Fig. 3. It will thus be seen that the gradual inclination of the edge 85 compensates for the different positions of the lever in its adjustment from left to right or vice versa and that the change of leverage on the pin 83 is compensated for in this way and a uniform motion is imparted thereto. Said arm 82 is fixed upon the forward end of a rock shaft 86, which extends parallel with the shaft 39 and is journaled at its forward end in the lug 53, and at its rear end in the bearing 54. Upon said rear end is carried an upwardly projecting rocker arm 87, to the upper end of which is connected by a screw 88, the left-hand end of a thrust link 89, whose right-hand end extends downwardly and is pivoted at 90 to the depending arm 91 of a bell crank, which is pivoted at 92 upon a bracket 93 fixed upon the forward end of a bracket 94, which usually supports both the carriage feeding pinion 21 and the escapement wheel 22. The horizontal arm 95 of said bell crank carries at its free end a roll 96, whose normal position is just beneath the carriage feeding rack 18, so that an inward thrust of the link 89 may, by rocking the bell crank, lift 110 the rack out of mesh with the pinion.

The column stops 44 are adjustably mounted upon a horizontal rack or bar which is designated generally as 97, and upon the lower face of which are cut teeth 98. The upper portion of the rack is provided with opposite dove-tail grooves 99, whereby the rack is detachably supported at one end upon a bracket 100, and at the other end upon above mentioned arm 12 formed upon the carriage truck. The bracket 100 is dove-tailed at 101 to match the grooves on the rack, and is secured upon the carriage by screws 102. The arm 12 is similarly dove-tailed at 103. At its left-hand end the rack is provided with a handle 104, whereby it may be drawn outwardly and disengaged from the carriage, whereupon the column stops may be arranged at any desired intervals along said rack. The latter may then be remounted upon the carriage, a vertical stop plate 105 being fixed upon the farther side of the arm 12, for the rack to abut against when it is slid endwise to position. The rack is provided with a central longitudi-

5 dinal slot or opening 106, to receive upwardly projecting centrally arranged, opposite fingers 107 provided upon the column stops 44, said fingers being separated at 108 to enable them to be sprung slightly towards each 10 other. The slot 106 is formed with downwardly and inwardly converging inclined walls for coaction with the fingers, the narrow portion of the said slot communicating with the notches between the rack teeth 98, and the tips of the spring fingers being preferably rounded 15 and arranged close together so that they may be inserted through a notch upwardly into the opening 106, whereupon the stop may be pushed to its seat, the fingers then diverging or springing outwardly to fit the converging walls of said opening, so as to sustain the column 20 stop. The fingers are preferably formed integrally with the stop blade or plate and in the same plane therewith, and the device may be cheaply stamped from sheet metal.

In operation, the handle 104 is grasped and the column 25 stop rack pulled out of the machine, whereupon the stops 44 are inserted at any desired intervals between the teeth 98 of the rack. The latter is then remounted upon the carriage and pushed into position against the stop plate 105; whereupon the paper carriage 30 is pushed to the right-hand of the machine and then the paper to be written on inserted in the usual manner. By means of the button 51 and the handle 50 the rack 37 is drawn towards the right, until the index 35 80 registers with a division upon the scale 81 corresponding with the denomination of the number to be written. If the denomination is hundreds, the rack is moved until the index occupies the position shown at Fig. 4. During this movement, the pinion 38, shaft 39 and bevel pinion 40 are rotated, thus imparting a rotary movement to the bevel gear 41 and cam-plate 42. Said cam-plate acts upon the pin 69, which projects upwardly from the denomination stop carrier, and forces both the pin and the carrier towards the right, or in a direction opposite to the letter feeding 40 movements of the paper carriage. At the initial portion of the sliding movement the denomination stop carrier is elevated by the co-action of the inclined faces 76 and 77, whereby the denomination stop 43 is brought into position for engagement with a column stop. It 45 Will be perceived that this upward movement of the stop 43 is in a direction transverse to the run of the carriage. As the rotary movement of the cam plate continues, the stop carrier 70 is slid towards the right until the position illustrated at Figs. 7 and 8 is reached, 50 which corresponds to the position of the index 80, at Fig. 4. Then the button 51 is pushed downwardly to 55 vibrate the lever 50 and the arm 82, whereby the shaft 86 is rocked and the arm 87 vibrated pushing the link 89 to the right, swinging the bell crank arm 91 and elevating the arm 95 and roll 96, and lifting the carriage feeding rack 18 out of engagement with its pinion 81, so that the carriage may be drawn rapidly towards the left by the spring barrel 15. The carriage is then arrested by the engagement of the first column stop 44 with the stop 43. By reason of the co-action of said stop 43 with the working edge 67 of the cam plate, the former is enabled to arrest the carriage positively and without danger of becoming displaced by the impact of the carriage, since said stop is solidly backed by the cam-plate, the pivot of the latter being substantially

in line with the slideway 71, so that the pressure of the carriage and stop against the cam plate is applied in a substantially radial direction, and hence is ineffective to rotate the plate upon its pivot. The carriage being thus arrested, the button 51 is permitted to rise under the influence of a returning spring 109 coiled about the shaft 86, and an independent spring 111 on the hub 52, the link 89 being at the same time drawn to the left by the rocker arm 87, and the carriage feeding rack 18 being hence permitted to drop into reengagement 75 with its pinion. It will be understood that at this time the carriage is still detained by the denomination stop 43, and hence there is no danger of a mis-step or spurious feeding movement of the carriage. Preferably the parts are so proportioned that the carriage is arrested 80 at a point slightly to the right of its proper printing position, so that when subsequent disengagement takes place between the denomination stop and the carriage stop, there may be a slight "drop" of the carriage, whereby it is brought to its proper printing position. 85 After the upward movement of the finger piece 51, the latter is allowed to return to its normal position to the left, through the pinion 38 and rack 37, under the influence of a spring 110 coiled about the shaft 39, which also returns the segment 41 and cam plate 42 to normal position. During said return of the cam plate the eccentric slot 66 therein works upon the pin 68 and draws the stop carrier to the left, when it drops to its normal position. Then the type keys are operated to imprint the desired number upon the paper. The 90 95 operation of positioning the denomination stop and releasing the carriage is repeated for every column upon the page.

Many changes may be made within the scope of the invention, parts of which may be used without others. 100

What I claim as new and desire to secure by Letters Patent, is:—

1. In a typewriting and tabulating mechanism, the combination of a carriage, two co-acting stops therefor, one of which is normally out of the path of the other, a rotary shaft having at one end means for adjusting one of said stops in a direction parallel with the run of the carriage, a finger-piece connected to the other end of said shaft, and means controlled by said finger-piece for releasing the carriage. 105

2. In a typewriting and tabulating mechanism, the combination of a carriage, a single denomination stop, a co-operating stop having a single contact face thereon, a rotary shaft having at one end means for moving said denomination stop in a direction parallel with the run of the carriage to different denominational positions, the extent to which said denomination stop is moved determining the denominational position at which said carriage will be arrested, a finger-piece connected to the other end of the shaft, and means controlled by said finger-piece for releasing the carriage. 110

3. In a typewriting and tabulating mechanism, the combination of a carriage, a column-stop carried by the carriage, a denomination stop on the frame of the machine, a cam for moving said denomination stop in the direction of the travel of the carriage, a finger-piece, connections between said cam and said finger-piece, and means controlled by said finger-piece for releasing the carriage. 125

4. In a typewriting and tabulating mechanism, the combination of a carriage, a column-stop rack carried by the carriage, a denomination stop carried by the frame of the machine, a cam for moving said denomination stop transversely and adjusting it to different denominational positions, and a finger piece connected to said cam. 130

5. In a typewriting and tabulating mechanism, the combination of a carriage, a column stop, a denomination stop, 135

- a cam connected to and adapted to actuate said stop, a shaft for operating said cam, a finger piece for operating said shaft, and means controlled by said finger piece for releasing the carriage. 80
5. In a typewriting and tabulating mechanism, the combination of a carriage, a denomination stop, a cam, gear 41 fixed to said cam, shaft 39 having pinion 40 in mesh with said gear, and means for operating said shaft. 85
7. In a typewriting and tabulating mechanism, the combination of a carriage, a denomination stop, a co-acting stop, a cam plate having an eccentric slot, a device connected to said denomination stop and working in said slot, and means for rotating said cam plate. 90
8. In a typewriting and tabulating mechanism, the combination of a carriage, a stop carrier, a cam plate engaging a projection upon said stop carrier, and means for moving said cam plate so as to adjust said stop carrier in a direction longitudinally of said carriage. 95
9. In a typewriting and tabulating mechanism, the combination of a carriage, a stop, means cooperating with said stop to arrest the carriage, cam mechanism for both moving said stop transversely of the run of the carriage and adjusting said stop to different denominational positions, key controlled means for actuating said cam mechanism, and carriage releasing means under the control of said key controlled means. 100
10. In a typewriting and tabulating mechanism, the combination with a carriage of a stop, a co-acting stop, means for moving one of said stops in a direction parallel to the run of said carriage, and a cam for simultaneously moving said stop in a direction transversely to the run of the carriage. 105
11. In a typewriting and tabulating mechanism, the combination with a carriage, of a stop movable longitudinally of the carriage and having a cam as 77, whereby said stop may be moved in a direction transversely to the run of the carriage. 110
12. In a typewriting and tabulating mechanism, the combination of a carriage, a stop carrier having a cam as 77, a projection on said stop carrier, a movable cam as 42, for engaging said projection, and a finger piece for moving said cam 42. 115
13. In a typewriting and tabulating mechanism, the combination of a carriage, a stop carrier, a slideway therefor comprising cam block 74 and sides 73, projection 69 upon said stop carrier, cam plate 42 having eccentric slot 66, and means for rotating said cam plate. 120
14. In a typewriting and tabulating mechanism, the combination of a carriage, a denomination stop, a key actuated cam for moving said denomination stop to different denominational positions, said cam having a working edge which engages said stop to enable the latter to sustain the shock of arresting the carriage, and means controlled by the key of said cam for releasing the carriage. 125
15. In a typewriting and tabulating mechanism, the combination of a carriage, a denomination stop carrier, a slideway for said carrier, means on said slideway for causing transverse movement of the carrier, cam plate 42 having a slot 66 and working edge 67, and means for rotating said cam plate. 130
16. In a typewriting and tabulating mechanism, the combination of a carriage having a stop, a stop carrier 70, a slideway therefor comprising cam plate 74 and sides 73, projection 69 upon said carrier, cam-plate 42 having eccentric slot 66, bevel gear 41, bevel pinion 40, shaft 39, and means for rotating said shaft. 135
17. In a typewriting and tabulating mechanism, the combination of a carriage, a stop, a co-acting stop, a shaft as 39 operatively connected to one of said stops, a rack as 37 engaging a pinion on said shaft, and a finger piece upon said rack. 140
18. In a typewriting and tabulating mechanism, the combination with a carriage and a column stop, of a denomination stop, a shaft connected thereto, a finger piece for rotating said shaft, an index which is moved to different positions by the actuation of the finger piece to indicate the denominational position of the denomination stop, and a cooperating scale. 145
19. In a typewriting and tabulating mechanism, the combination with a carriage and a column stop, of a denomination stop, a shaft connected thereto, a pinion upon said shaft, a rack engaging said pinion, a finger piece, an index and a cooperating scale. 150
20. In a typewriting and tabulating mechanism, the combination with a carriage, of a column stop thereon, a denomination stop supported upon the frame, a shaft connected to said denomination stop, bearings for said shaft, a rack in engagement with a pinion upon said shaft, and a bracket upon which said rack may slide. 155
21. In a typewriting and tabulating mechanism, the combination of a carriage, a column stop, a denomination stop, a shaft operatively connected to one of said stops and adapted to slide it in the direction of the travel of the carriage to different denominational positions, a finger piece connected to said shaft, a spring as 110 for returning said shaft and its stop to normal position, and means controlled by said finger piece for releasing the carriage. 90
22. In a typewriting and tabulating mechanism, the combination of a carriage, a column stop, a denomination stop, a shaft connected to said denomination stop, a rack for operating said shaft, a slideway for said rack, and a returning spring. 100
23. In a typewriting and tabulating mechanism, the combination of a carriage, a platen thereon, a column stop and a denomination stop arranged in rear of the platen, a forwardly extending shaft operatively connected at its rear end to one of said stops, a sliding finger piece arranged at the forward end of said shaft, an index which is adapted to be moved to different positions by said finger piece, and a scale which cooperates with said index. 105
24. In a typewriting machine and tabulating mechanism, the combination of a power driven carriage, feeding devices therefor, a stop, a co-acting movable stop, means for affording a transverse movement of the movable stop into the path of the stop with which it cooperates, independent actuating means for transmitting a movement to the movable stop in the direction of the travel of the carriage to adjust said movable stop to different denominational positions and to automatically effect a transverse movement thereof into the path of the stop with which it cooperates, a key controlling said actuating means, the transverse movement and denominational positioning of the movable stop being effected by a movement of said key in one direction, and means controlled by a movement of said key in another direction to effect the release of the carriage. 110
25. In a typewriting and tabulating mechanism, the combination of a power driven carriage, letter feeding devices, a stop, a co-acting stop, a shaft connected at one end to one of said stops, and adapted to slide it in the direction of the travel of the carriage to different denominational positions, a finger piece for rotating said shaft, and means controlled by said finger piece for releasing the carriage from the control of its letter feeding devices. 115
26. In a typewriting machine, the combination of a power driven carriage, letter feeding devices, column stop rack thereon, a denomination stop supported upon the frame of the machine, a shaft connected at one end to said denomination stop and adapted to slide it in the direction of the travel of the carriage to different denominational positions, a finger piece connected to the other end of said shaft, and means controlled by said finger piece for releasing the carriage from the control of its letter feeding devices. 120
27. In a typewriting and tabulating mechanism, the combination of a power driven carriage, letter feeding devices, a column stop, a denomination stop, a cam for moving said denomination stop longitudinally of the carriage, a finger piece, connections between said cam and said finger piece, and means controlled by said finger piece for releasing the carriage from the control of its letter feeding devices. 125
28. In a typewriting and tabulating mechanism, the combination of a power driven carriage, letter feeding devices, a column stop rack thereon, a denomination stop mounted upon the framework, a cam for moving said denomination stop transversely and adjusting it to different denominational positions, a finger piece connected to said

- cam, and means controlled by said finger piece for releasing the carriage from the control of its letter feeding devices.
29. In a typewriting and tabulating mechanism, the combination of a power driven carriage, letter feeding devices, a column stop thereon, a denomination stop mounted upon the framework, a cam connected to said stop, a forwardly extending shaft for operating said cam, a finger piece arranged at the forward end of said shaft, and means controlled by said finger piece for releasing the carriage from the control of its letter feeding devices.
30. In a typewriting and tabulating mechanism, the combination of a power driven carriage, a column stop adjustable thereon, a denomination stop upon the framework, a cam mechanism for both moving said stop transversely of the run of the carriage and adjusting said stop to different denominational positions, and carriage releasing mechanism.
31. In a typewriting and tabulating mechanism, the combination with a power driven carriage and a column stop thereon, of a denomination stop mounted upon the framework, means for moving said denomination stop in a direction parallel to the run of said carriage, a cam for simultaneously moving said stop in a direction transversely to the run of the carriage, and carriage releasing devices.
32. In a typewriting and tabulating mechanism, the combination of a power driven carriage, co-acting stops, a key, denomination-determining mechanism controlled by said key, letter-feeding rack 18 upon the carriage, pinion 21, bell crank 91, 95, for releasing said rack, link 89 connected to said bell crank, shaft 86 having arm 87 connected to said link, arm 82 on said shaft, and means for enabling said key to operate said arm.
33. In a typewriting and tabulating mechanism, the combination of a power driven carriage, co-acting stops, a key denomination determining mechanism controlled by said key, rack 18 upon the carriage, pinion 21, bell crank 91, 95, for releasing said rack, link 89 connected to said bell crank, shaft 86 having arm 87 connected to said link, arm 82 on said shaft, means for enabling said key to operate said arm, and returning spring 109 on said shaft.
34. In a typewriting and tabulating mechanism, the combination of a power driven carriage, a stop thereon, a denomination stop upon the framework, a shaft operatively connected to said denomination stop, a pinion on said shaft, a rack in mesh with the pinion, a lever pivoted upon said rack, and a carriage releasing device controlled by said lever.
35. In a typewriting and tabulating mechanism, the combination of a power driven carriage, a stop thereon, a denomination stop upon the framework, a shaft operatively connected to said denomination stop, a pinion on said shaft, a rack in mesh with the pinion, a bracket upon which said rack may slide, a lever pivoted upon said rack, and a carriage releasing arm engaged by said lever.
36. In a typewriting and tabulating mechanism, the combination of a power driven carriage, a column stop thereon, a denomination stop upon the framework, shaft 39 connected to said denomination stop, rack 37, lever 50 pivoted upon said rack, shaft 86, having arm 82 controlled by said lever, and also having arm 87, link 89 connected to arm 87, bell crank 91, 95, connected to said link, and carriage feeding rack 18 movable by said bell crank.
37. In a typewriting and tabulating mechanism, the combination of a power driven carriage, a column stop thereon, a denomination stop upon the framework, cam mechanism for operating said denomination stop, shaft 39 for controlling said cam mechanism, pinion 38 upon said shaft, rack 37 in mesh with said pinion, lever 50 pivoted upon said rack, arm 82 having a lateral pin 83 engaging slot 84 formed in said lever, shaft 86 carrying said arm 82 and having at its rear end arm 87, and means controlled by said arm 87 for releasing the carriage from the control of its letter feeding devices.
38. In a typewriting and tabulating mechanism, the combination of a power driven carriage, letter feeding devices therefor, a stop, a co-acting stop, an endwise movable lever as 50 connected by rack and pinion to means for adjusting one of said stops, and carriage releasing devices actuated by a downward movement of said lever at any longitudinal position thereof.
39. In a typewriting and tabulating mechanism, the combination of a power driven carriage, letter feeding devices, a stop, a co-acting stop, lever 50 connected by rack 37 and pinion 38 to means for adjusting one of said stops, index 86, scale 81, and carriage-releasing devices controlled by said lever at all positions of said rack. 85
40. In a typewriting and tabulating mechanism, the combination of a power driven carriage, letter feeding devices therefor, a column stop thereon, a denomination stop upon the framework, a lever, as 50, connected to a rack 37, means controlled by said rack for moving said denomination stop both longitudinally and transversely of the run of the carriage, and devices, movable by a movement of said lever independently of said rack and at any longitudinal position thereof, for releasing the carriage from the control of its letter feeding devices. 90
41. In a typewriting and tabulating mechanism, the combination of a top plate a power driven carriage adapted to move from side to side over said top plate, a column stop supported upon the rear portion of the carriage, a denomination stop adapted to said column stop and supported upon the top plate, cam mechanism for moving said denomination stop, a forwardly extending shaft operatively connected to said cam mechanism, a rack and pinion at the forward end of said shaft, a lever mounted upon said rack, an index, and a shaft having a part movable by said lever and connected to means for releasing the carriage. 100
42. In a typewriting and tabulating mechanism, a detachable column stop rack provided with dove-tailed grooves which engage corresponding grooves formed in arms provided upon said carriage. 110
43. In a typewriting and tabulating mechanism, a detachable column stop rack having a finger piece 104 and dove-tailed grooves 99 adapted to corresponding grooves formed in arms 100 and 12 upon said carriage. 115
44. In a typewriting and tabulating mechanism, the combination of carriage, arms 12 and 100 thereon, a detachable column stop rack having grooves corresponding to grooves in said arms 12 and 100, and stop 105 against which said rack may abut when inserted into the carriage. 120
45. In combination with a column stop rack or bar having upon one side teeth 98 and having also a longitudinal slot or opening 106, communicating with the notches between the teeth 98, a column stop having spring fingers for engaging said slot. 125
46. A column stop rack or bar having teeth 98 upon one side or face thereof, and also having a longitudinal central slot 106 having converging sides and communicating at its narrow portion with the notches between the teeth 98. 130
47. A column stop rack or bar having teeth 98, dove-tailed grooves 99, and central longitudinal slot 106 having converging sides. 135
48. A plate-like column stop having a blade portion, and integral opposite cooperative spring fingers projecting from the blade portion. 135
49. A plate-like column stop having a blade portion, and cooperative spring fingers projecting from the blade portion and to the plane thereof. 140
50. A column stop comprising a blade portion, and diverging spring fingers projecting therefrom. 140
51. A column stop comprising a blade portion, and integral diverging spring fingers projecting laterally from the central portion thereof. 145
52. In a typewriting and tabulating mechanism, the combination of a rack or bar having teeth upon one side thereof and also having a slot or opening narrower at one portion, said narrow portion communicating with the notches between said teeth, and a column stop blade having spring fingers for engaging said slot. 150
53. In a typewriting and tabulating mechanism, the combination with a carriage, of a rack or bar having teeth 98 and a slot 106 having converging sides, said slot communicating at its narrower portion with the notches between said teeth, and column stops 44 having spring fingers 107 adapted to project into said opening 106. 155
54. A self-sustaining column stop having spring catches or fingers arranged close together and adapted to be inserted together into an opening formed in a column stop bar. 160

55. In a typewriting machine and tabulating mechanism, the combination of a carriage, stops normally out of each other's path, and one of which is a denominational stop movable in the direction of the travel of the carriage to determine the denominational position of arrest of the carriage and which is also movable transversely of the travel of the carriage to bring the stops one into the path of the other, the movement of the denominational stop in the direction of the travel of the carriage being also effective to move it transversely, means for moving the denominational stop, and means under control of said movable means for releasing the carriage.

56. In a tabulating mechanism for typewriting ma-

chines, the combination of a toothed stop bar and a detachable and adjustable stop carried by said bar and adapted to be held in place in its spaces between the teeth on the bar, said stop having an integral spring which is adapted to engage the bar and hold the stop against accidental detachment therefrom. 15

Signed at the borough of Manhattan, city of New York, 20
in the county of New York, and State of New York, this
23rd day of January, A. D. 1901.

CHARLES H. SHEPARD.
